CABLE CLAMP

Application filed February 24, 1931. Serial No. 517,837.

My invention relates to that class of cable clamps which are employed in connecting a guy wire cable or the like to an anchor rod.

My object is to provide a clamp of this character of simple, durable and inexpensive construction, which may be made of cast malleable metal, and without machining any other than screw threads, and to which a cable stretched taut may be readily, quickly and easily applied and firmly and securely anchored.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of a cable clamp embodying my invention with a cable clamped therein.

Figure 2 shows a side elevation of same partly in section.

Figure 3 shows a top or plan view of the body portion of the clamp with the upper clamping member and bolt removed.

Figure 4 shows a top view of the lower clamping member; and

Figure 5 shows an inverted plan view of the upper clamping member.

Referring to the accompanying drawings, I have used the reference numeral 10 to indicate generally the body portion of the clamp.

At one end it is preferably provided with an enlarged portion 11, having a screw threaded opening 12 to receive a screw threaded anchor rod, not shown. The body portion is preferably substantially oval and substantially flat on its upper and lower surfaces. The upper surface, however, is provided with a groove 13 to receive a cable 14, as shown in Figure 3, and toward the rear end of the top surface there is a raised post 15, for purposes hereinafter made clear. In the center of the body portion is a screw threaded bolt opening in which a bolt 16 is seated.

Rotatively mounted upon the bolt 16 is a sleeve 17 having its upper end made of angular formation to receive a wrench. On the lower end of the sleeve 17 are two outwardly

extended arms 18, with their outer edges of wedge shape, and these are so arranged that when the sleeve 17 is turned to one position, the arms 18 will assume the position shown by dotted lines at 19 in Figure 3, and when the arms 18 are turned to the position shown by solid lines in Figure 3, these wedge surfaces engage and clamp adjacent portions of the cable against the raised ribs 20 at the outer sides of the body portion.

A pull upon the cable 14 in the direction of the arrow shown in Figure 3 will cause the wedges to firmly grip the cable, the gripping action of which increases as the tension upon the cable increases.

Mounted on top of the body portion is an upper gripping member 21, having an opening therein to loosely receive the sleeve 17. This gripping member is formed with a groove 22 shaped substantially like the groove 13 and designed to receive the cable 14. When the cable is in position in the grooves 13 and 22, as shown in Figure 2, and when the clamping member 21 is pressed against the body portion 10, then the cable will be firmly clamped between these two members, but the adjacent surfaces at the sides of the groove will be slightly spaced apart.

At the forward end of the clamping member 21, the outer rib, which forms the groove 22, is cut away so that the cable may extend beyond the gripping member.

I have also provided a second gripping member to cooperate with the body 10, substantially like the gripping member 21, and indicated generally by the numeral 23, and has a cable groove 24. It is rotatively mounted on the lower end of the bolt 16, and a nut 25 and lock washer 26 are provided for gripping it against the body portion 10 and holding it in that position.

In some instances I find that the wedge locking device 17 and 18 is unnecessary, and when that is not used, the device is operated as follows:

First the bolt is screwed upwardly until the upper clamping member 21 has moved to position spaced apart from the body 10 far enough to permit the insertion of the cable into the grooves 13 and 22 from the en-

tire circumference inwardly. That is to say, the cable is simply wrapped about the clamping device until it enters the grooves and is engaged by the post 15. Then a block and tackle is applied to the end of the cable, shown at the right in Figure 3, and the cable is drawn taut. When this has been done, the bolt 16 is screwed down to firmly hold the clamping member 21 against the body 10. Then the block and tackle is removed so that the end of the cable is free. This free end is then bent downwardly over the end of the body 10, as shown at 27 in Figure 2, and is wrapped around the clamping member 23, in the same manner as it was around the clamping member 21 before described, until it is contained within the groove 24 and the corresponding groove on the under side of the body 10, as shown in Figure 2, and its free end may then be extended outwardly. Then the nut 25 is manipulated to firmly clamp the clamping member 23 against the body 10.

This forms a clamp sufficient to hold the cable against strains to such an extent that the cable will break before it slips in the clamp.

In some instances I prefer to have the end of the cable concealed within the clamp between the clamping member 23, and the body 10, but where a longer cable end is desired, the projecting end may be tied to the body portion of the cable by a wire 28, or in any other suitable manner.

When it is desired to again stretch the same cable, this may be done with my improved device very quickly and easily, because all that is necessary is to loosen the nut 25. Then unwrap the end portion of the cable from between the clamping member 23 and the body 10, and then apply a block and tackle to the loose end of the cable, and when this has been done, then it is only necessary to loosen the bolt 16 a slight amount, sufficiently to permit the block and tackle to draw the cable through a groove between the clamping members 21 and 10, and when the tension has been properly applied to the cable, the bolt 16 is tightened and the end of the cable secured in the same manner as before described.

When it is desired to use the wedge clamping device, it is not necessary to use the lower clamping member 23, although this may be done if desired for the purpose of concealing the end of the cable.

The operation of my clamping device when the wedge locking device is used is the same as that before described, except that the wedge is first placed in the position shown by dotted lines in Figure 3. Then after the cable has been stretched taut, the wedge member is moved to the position shown by solid lines in Figure 3, and then the bolt 16 is tightened to clamp the member 21 against the body

I have found in practice that the entire device may be manufactured at a considerably less cost than that for other articles now in use for the same purpose, and that an operator can save considerable time by the use of my improved clamp over that required for other clamping devices now in use. 70

I claim as my invention:

1. A cable clamp comprising a body portion having a substantially flat surface, a bolt seated in the body portion, a cable retaining post on said flat surface of the body, a sleeve rotatively mounted on the bolt, two wedges on the end of the sleeve adjacent to the body and so shaped that a cable may be passed around the bolt and the post and be supported by the post spaced apart from the wedges and the bolt when the wedges are in one position, and that when the sleeve is turned the wedges will engage the adjacent surfaces of the cable on both sides of the bolt, a clamping member loosely mounted upon the bolt and formed with an opening through which said sleeve is projected, and means on one of the clamping members for opposing the outward movement of the cable when engaged by the wedges. 80

2. A cable clamp device comprising a body portion and two clamping members, one on each side of the body portion, a bolt passed through both clamping members and having a screw threaded connection with said body portion, and a nut on the end of the bolt for drawing one of the clamping members toward the said body, said parts being so shaped that a portion of a cable may be passed around one side of the body portion and then stretched taut, then by turning the bolt one of the clamping members may be drawn toward the body to clamp the cable, then the free end portion of the cable may be wound around the opposite side of the body and finally by adjusting said nut, the free end of the cable may be clamped to the body by the other clamping member. 100

3. A cable clamp device comprising a body portion, means at one end thereof for connecting it to an anchor rod, said body portion being so shaped that a cable may be passed around it in the form of a U-shaped loop, then across to the other side of the body and then around said other side in the form of a second loop, a clamping member on each side of the body portion so shaped as to coact with the body portion in clamping a cable between them, and means for independently forcing each clamping member toward the body portion. 115
